DESIGN FOR A PIPE

George T. Ash, Washington, D. C.

Application September 21, 1945, Serial No. 122,240

Term of patent 7 years

(Cl. D85—8)

To all whom it may concern:

Be it known that I, George T. Ash, a citizen of the United States, residing in the city of Washington, District of Columbia, have invented a new, original, and ornamental Design for a Pipe, of which the following is a specification, reference being had to the accompanying drawing, forming part thereof.

Figure 1 is a front view of the pipe showing my new design; Fig. 2 is a side view of the pipe; Fig. 3 is a rear view of the pipe; Fig. 4 is a top view of the pipe; and Fig. 5 is a bottom plan view of the pipe showing my new design.

I claim:

The ornamental design for a pipe, as shown.
GEORGE T. ASH.
